UNITED STATES PATENT OFFICE.

PHILIP S. TELLER, OF ALAMEDA, CALIFORNIA.

CONTAINING-CAN.

SPECIFICATION forming part of Letters Patent No. 792,242, dated June 13, 1905.

Application filed May 12, 1902. Serial No. 106,909.

To all whom it may concern:

Be it known that I, PHILIP S. TELLER, a citizen of the United States, residing at Alameda, county of Alameda, State of California, have 5 invented an Improvement in Containing-Cans; and I hereby declare the following to be a full, clear, and exact description of the same.

My invention relates to improvements in containing-cans; and it is especially applicable to cans which are designed to contain butter and like substances and a saline or other solution in which the contained substances must be continually submerged.

My invention consists in such a construction of the can top or cover that a space or chamber is formed above the main body and contents of the can which can be filled with the liquid, so that the contents of the can will always be submerged, and in conjunction with 10 this is a filling-opening and a supplemental cap which is soldered or otherwise hermetically sealed over the opening after the filling is complete.

Referring to the accompanying drawings, 15 Figure 1 is a vertical section through a can embodying my invention. Fig. 2 is a plan of the top.

In the packing of butter it is desirable to place it in hermetically-sealed cans which 20 contain any desired or suitable quantity and to preserve the butter from deterioration by submerging it in a sufficiently-strong brine. These cans are conveniently made rectangular, but may be of any other suitable shape; but, 25 the butter being lighter than the liquid, when it is attempted to fill the can before the cover is sealed the butter will rise or float up in the liquid and prevent the liquid from flowing over and submerging the butter, and the part 30 which is thus left exposed soon becomes unfit for use.

It is the object of my invention to provide a means by which the butter will be constantly submerged in the liquid. This is effected by 35 forming an extension or chamber in the top of the can having such dimensions that the butter cannot move up into it; but it can be filled with the saline solution and afterward sealed. The solution will thus remain upon 40 the top and surrounding the butter within the

body of the can and prevent it from ever being exposed above the surface of the solution. In addition to this the shape of the top is such as to prevent the cans being conveniently reversed when stored or shipped.

As illustrated in the present invention, A is a portion of the body of a can designed to contain butter. B is a cap or cover. These two parts are in the present case shown as being made rectangular, and the cover can be 55 soldered or otherwise permanently fixed to the top of the can.

In my invention I form a cover with the raised chamber 2, which in the present case is shown as convex; but it may be of any suitable or desired shape. Such a chamber may be stamped in the material of which the main cover is made, so that they can be very rapidly formed. In the center and top of the extension or chamber a small hole is made, as at 3, 60 and a cap 4 is adapted to fit over this hole and to seal it after the can has been filled. The shape of the extension-chamber is such that if the can is filled with butter, which would be essentially rectangular in shape, it is afterward filled with the salt solution (the brine) 65 and the extension or chamber is also filled with brine. The shape of the chamber is such that the butter cannot pass up into it, being stopped by the angles 5 of the cover; but the liquid 70 with which the hole is filled will constantly submerge the butter and prevent its being exposed to the air. The small hole 3 allows the can to be filled full of the salt solution, including the extended chamber, and after this is 75 done the small cap 4 is soldered over the hole, thus completing the work. It will be understood that this chamber may be made of any suitable or desired shape without departing 80 from my invention.

Having thus described my invention, what I claim, and desire to secure by Letters Patent, is—

1. An improved butter-can having a metal body rectangular in cross-section and of substantially uniform diameter throughout its length, said body having the top edge formed with a divergent upwardly-extending smooth-surfaced flange; and a cover having a dome-shaped centrally-located chamber, to maintain 95 90 100

a preservative solution above the butter, and having an upturned divergent smooth-surfaced flange fitting within the flange of the body said cover having at the base of the flange 5 and connecting said flange with the base of the dome-shaped portion, and an annular portion 5 adapted to prevent the butter rising into the dome-shaped chamber.

2. An original package consisting of a can 10 having a sheet-metal body of substantially even diameter, and having the top formed with a divergent upwardly-extending flange, a top having a dome-shaped centrally-located chamber, a surrounding upwardly-divergent flange 15 and an intermediate annular portion to form

a shoulder or stop, said body containing a liquid preservative and a block of butter submerged therein, and said dome-shaped chamber adapted to retain a portion of the preservative above the butter, and said annular portion serving to prevent the butter rising into the chamber and to insure its being always submerged in the preservative. 20

In witness whereof I have hereunto set my hand.
